F. SOLEY.

PADLOCK,

APPLICATION FILED MAR. 31, 1921.

1,384,682.

Patented July 12, 1921.

UNITED STATES PATENT OFFICE.

FRANK SOLEY, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

PADLOCK.

1,384,682.

Specification of Letters Patent.

Patented July 12, 1921.

Application filed March 31, 1921. Serial No. 457,189.

To all whom it may concern:

Be it known that I, FRANK SOLEY, a citizen of the United States, residing in Philadelphia, Pennsylvania, have invented certain Improvements in Padlocks, of which the following is a specification.

My invention relates to certain improvements in padlocks in which the shackle is raised by a spring clear of its socket and 10 which can be turned to either side when opened.

One object of the invention is to provide a heavy cast casing, which incloses the mechanism of the lock, and plates on which 15 the parts of the lock are assembled, which are detachably mounted in the casing, and side armor plates.

A further object of the invention is to improve the mechanism by which the shackle 20 is held in the locked position.

A still further object of the invention is to provide means for holding the key guide in a stationary position.

These objects I attain in the following 25 manner, reference being had to the accompanying drawings, in which:

Figure 1 is a side view of my improved lock with one of the cover plates and one of the carrying plates removed, and showing 30 the locking dog engaging the shackle;

Fig. 2 is a view, similar to Fig. 1, with the carrying plates in position;

Fig. 3 is a view, similar to Fig. 1, showing the dog retracted and the shackle raised;

Fig. 4 is a sectional view on the line 4-4, Fig. 1;

Fig. 5 is a perspective view showing the casing of the lock;

Fig. 6 is a perspective view showing one 40 of the cover plates;

Fig. 7 is a perspective view showing the two holding plates;

Figs. 8 and 9 are views of the shackle;

Fig. 10 is a perspective view of the dog 45 release lever;

Fig. 11 is a perspective view of one of the series of tumblers;

Fig. 12 is a detached perspective view of the locking dog;

Fig. 13 is a detached perspective view of the key post; and

Fig. 14 is a perspective view of the key.

Referring to the drawings, 1 is the casing of the lock made of cast metal of the form

shown in Fig. 5, having a deep opening 2 55 for the long leg 4 of the shackle 3, and a socket 6 for the short leg 5 of the shackle. The front and rear of the casing are recessed, as shown, to receive the armor plates 7, Fig. 6, each of which has three countersunk openings 8 through which extend the rivets 9, which secure the plates to the casing. 10, 11 and 12 are projections in the interior of the casing. These projections are narrower than the recessed portions to receive the 60 carrying plates 13 and 14, which fit directly back of the armor plates 7, as clearly shown in Fig. 4. On the plate 13 are pins 15 and 16, which extend into openings in the plate 14 so that the two plates are brought into 70 alinement. Each of the plates is recessed at 17 to clear the countersunk portions 8 of the armor or cover plates 7.

18 is a guide, Fig. 13, having a cylindrical portion 19 and an octagonal portion 20. 75 The cylindrical portion of the key guide fits in the cylindrical opening 21 in the casing, Fig. 5, while the octagonal portion 20 fits between the two projections 11 and 12. These projections prevent the key guide 80 from turning. The key guide has a slot 22 for the reception of a key of the type illustrated in Fig. 14, in the present instance.

The pin 15 is the pivot pin for the locking dog 23, Fig. 12, which has two arms 24 connected by a locking member 25, which enters the notch 26 in the long leg 4 of the shackle 3 and holds the shackle in the locked position. Projecting from one of the arms 24 is a lug 27. This lug is engaged by the dog 85 operating lever 28, Fig. 10, which is pivoted to the pin 16. This lever has a recess 29 into which extends the locking member 25 of the dog, when retracted, as shown in Fig. 3, so as to enable it to enter the notches 30 90 in the tumblers 31, when the notches of the tumblers are brought into alinement. The tumblers 31 are mounted in the pivot pins 16 and each tumbler has a spring 32 of the ordinary construction, which bears against a lug 33 on the casing. In the present instance, I have shown six tumblers, but the 100 number and shape of the tumblers may be varied as desired.

It will be noticed in Fig. 10 that the portion of the dog operating lever against which the key rests may be of different lengths, as shown at 34. The dotted lines in Fig. 10

denote a blank before the portion 34 is reduced so that by increasing or diminishing the length of the portion 34 a number of key changes can be made.

The long leg 4 of the shackle is cut away at the back, as at 35, and a stop pin 36 extends through an opening 37 in the casing and through the space at the back of the shackle. This pin limits the movement of the shackle. The shackle is cut away at 38 to allow the shackle to turn without being interfered with by the pin. A spring 39, of the ordinary construction, is located at the bottom of the socket 2 in the casing and rests in a socket in the long leg 4 of the shackle so that, when the shackle is released from the dog, the spring projects it to the position shown in Fig. 3. The lower portions of the plates 13 and 14 bear upon the inner end of the key guide, as shown in Figs. 2 and 4, locking the key guide against longitudinal movement.

I preferably stiffen the plates 13 and 14 by a series of ribs, which, in the present instance, radiate from a central projection, as shown in Figs. 4 and 7. I also dish the armor plates 7, as in Fig. 4. Thus, the two plates at each side of the lock are materially stiffened so as to resist any hammering action to break the lock and, as I contemplate making the casing of cast steel, it will be almost impossible to destroy the lock by the present methods.

The parts of the lock are carried by plates independently of the casing, so that the parts can be readily assembled, after which the armor plates are placed in position and secured by rivets, or other fastenings.

I claim:

1. The combination in a padlock, of a casing; a shackle mounted in the casing, the long leg of the shackle having a notch; a locking dog pivotally mounted in the casing and arranged to enter the notch in the shackle; a dog operating lever; and a notched tumbler, said locking dog having a locking member arranged to enter the notch in the tumbler and having a projecting lug against which the dog operating lever strikes, when actuated by the key.

2. The combination in a lock, of a casing having an opening at the bottom; a key guide mounted in the opening, said key guide having flat sides and the casing having walls between which fits the flat portion of the key guide; and plates mounted in the casing of the lock and resting against the inner end of the key guide so as to hold the key guide in position in the casing.

3. The combination of a casing recessed at each side, two carrying plates, one located

on one side of the casing and the other located on the opposite side thereof; locking mechanism mounted on the carrying plates; a shackle located in the casing and arranged to be engaged by the locking mechanism; and plates located over the carrying plates and secured to the casing.

4. The combination of a casing recessed at each side and having internal projections; a key guide located in the casing and held from turning by two of the internal projections; two carrying plates, one mounted on each side of the casing; locking mechanism carried by said plates; a shackle located in the casing and arranged to be engaged by the locking mechanism, said carrying plates fitting against the inner end of the key guide to hold the key guide in position; and cover plates inclosing the carrying plates and the mechanism of the lock.

5. The combination in a padlock, of a casing having an opening extending therethrough; internal projections in the casing; a shackle having a long leg extending into an opening in the casing; two carrying plates, one on each side of the opening in the casing; a locking dog mounted on one pin and having a locking member engaging the shackle; a tumbler; a dog operating lever pivotally mounted on the other pin, both the tumbler and the lever having a notch to receive the locking member of the dog, the dog also having a projection extending over the operating lever so that when a key is inserted in the lock the operating lever will be forced against the projections and will withdraw the locking dog, said casing being recessed around the opening; a cover plate mounted in each recess and inclosing the carrying plates; and rivets retaining the cover plates in position.

6. The combination in a lock, of a casing; a shackle mounted in the casing; a locking dog pivotally mounted in the casing and arranged to engage the shackle; a pivoted tumbler; and a dog operating lever, both being arranged to be engaged by a key, said dog operating lever having a projection against which the end of the key comes in contact, said projection being capable of being reduced so as to make key changes.

7. The combination of a casing recessed at each side; two carrying plates for the mechanism of the lock, each plate being ribbed, one plate being located on one side of the casing and the other plate being located on the opposite side thereof; a shackle in the casing; and dished armor plates located on each side of the casing and inclosing the carrying plates.

FRANK SOLEY.
